ALIGNED-LEVER BUCKLE MECHANISM
Andrew G. Carter, 2930 Lake Drive SE,
Grand Rapids, Mich.
Filed Feb. 1, 1963, Ser. No. 255,587
7 Claims. (Cl. 24—230)

This invention relates to the construction of safety belt buckles of the type actuated by a pivoted lever. This type of mechanism is well-established, and the movement of the lever is normally used to disengage the locking mechanism to permit separation of the sections of the buckle. In the preferred form of the invention the lever positions a cam which normally maintains the lateral interengagement of abutments and recesses on the opposite sections of the buckle, respectively, for the transmission of forces resulting from belt tension. Several features of the invention are also applicable to the "dog"-type mechanism, in which a movable biased latch on one buckle section engages a recess or abutment on the opposite buckle section. Applicant has always found it preferable to transmit the belt forces through components that are fixed to the respective belt sections, rather than movable. This arrangement keeps the locking mechanism relatively free from forces resulting from belt tension, and removes the need to overcome high friction complications on release under load. This is the factor accounting for the preference in favor of the cam-type mechanism.

While the use of lever-actuated buckle mechanism is well known in this art, it has been the practice to mount the lever for pivot movement in such a direction that a large component of the manual release force tends to pull the buckle section containing the mechanism in the direction of normal belt tension, particularly when the lever is near the full release position. In other words, the buckle sections may be unlocked, but the release force on the lever continues to hold one belt section closely about the wearer. In normal release (as opposed to crash conditions), the relatively light belt tension is thus taken on one side of the belt. There usually is insufficient tension remaining in the opposite side to pull the unlocked buckle sections apart, and the result is to make disengagement of the belt a two-handed procedure.

The factor responsible for this characteristic of conventional lever mechanisms is that the pivot shaft supporting the lever has usually been coaxial with rotatively mounted cams or latch dogs, and these have uniformly been placed on the side of one buckle section which is normally closest to the opposite buckle section. The handle lever has normally extended back along the belt from the pivot point, which establishes the geometrical relationship of the conventional lever mechanism. As such, a lever swings outward on release, it also moves toward the opposite side on the belt against the action of the lever return spring.

It is the purpose of this invention to realign the movement of the lever so that the manual forces applied to it near the release position will tend to throw the buckle sections apart, rather than hold them together. Disengagement of an occupant from the belt then becomes a simple one-handed movement which can be continued to carry the belt section completely clear of his lap. One of the principal problems encountered in designing this improved mechanism has been the necessity of providing a locking cam capable of movement in opposite directions. Engagement of the buckle sections (without swinging out the handle) obviously involves a rotation of the cam in a direction which is opposite to the movement of the cam induced by the handle as it swings to the release position. Accommodating this dual direction of

2

movement, in addition to establishing the normal locking position of the cam, therefore becomes an important aspect of the preferred form of this invention.

A modified form of the invention provides for the desired alignment of the lever movement by eliminating the coaxial relationship between the cam and the handle pivot, and providing for a torque transfer from the lever over to the rotatable cam. In both forms of the invention, applicant has found it desirable to separate the portion of the buckle serving as an adjustable belt terminal from that which contains the active locking mechanism of the buckle. By displacing the adjustable terminal to a position further down the belt section, the mass normally associated with that portion of the device is removed from the lap of the wearer. This is a feature of substantial value, since many persons are inclined to object to the presence of a large piece of machinery in the lap. Anything tending to reduce this will substantially increase the saleability and use of safety belt equipment.

As a means of reducing the torque of the lever-return spring, and thus minimizing the forces necessary to actuate the mechanism, the invention also provides a counter-balancing of the lever which will tend to minimize the tendency for crash inertia to throw the lever to release position. The counterbalance arrangement therefore may permit the use of a very light return spring without sacrifice of safety, and therefore further favor the use of the safety belt by persons who normally just don't care to manipulate this equipment.

The several features of the invention will be discussed in further detail through an analysis of the particular embodiments illustrated in the accompanying drawings. In the drawings:

FIGURE 1 is an exploded view showing the buckle sections disengaged.

FIGURE 2 shows a plan view of the buckles in the engaged condition, with the lever swung back beyond the normal release position to expose the interior mechanism.

FIGURE 3 is a sectional elevation showing the buckle sections in the fully engaged and locked condition.

FIGURE 4 shows the buckle sections released.

FIGURE 5 is a sectional elevation showing an intermediate position in the engagement of the buckle sections.

FIGURE 6 is a plan view of a separate adjustable belt terminal of a modified form of the invention.

FIGURE 7 is a sectional elevation of the terminal on the plane 7—7 of FIGURE 6.

FIGURE 8 is a plan view showing the engaged buckle sections of the modification of the invention associated with the separate belt terminal.

FIGURE 9 is a sectional elevation on the plane 9—9 of FIGURE 8.

FIGURE 10 is a sectional elevation of a modified form of the invention in which the lever is mounted on a shaft which is not coaxial with the locking cams, with the device in the fully locked condition.

FIGURE 11 is a view of the release position of the mechanism shown in FIGURE 10.

Referring to the modification of the invention illustrated in FIGURES 1 through 5, the buckle section generally indicated at 20 is associated with the belt section 21, and provides a base plate 22 having the spaced parallel side flanges 23 and 24. The plate 22 has the apertures 25 and 26 disposed in a tongue portion 27, these apertures being adapted for interengagement with the abutments 28 and 29 on the opposite buckle section 30. The flanges 23 and 24 of the buckle section 20 have slots as shown at 31 and 32 for retaining the cylindrical

fixed bar 33 and the movable bar 34 of generally rectangular cross section. The bars 33 and 34 together form an adjustable terminal whereby the length of the belt may be adjusted to suit the needs of the particular occupant. The belt can be tightened by pulling on the free end 35. The length can be increased by pulling on the belt 21 while the opposite knurled ends of the bar 34 are grasped between the fingers to separate the bar 34 from the relatively fixed bar 33. Application of tension to the belt will then cause the bar 34 to move toward the bar 33, and entrap a portion of the belt between them in a jamming action sufficiently severe to resist belt tension.

The buckle section 30 includes a central plate portion 36 which contains the abutments 28 and 29, and is also provided with a slot 36a for receiving the belt 37. The spaced side flanges 38 and 39 include the lanced portions 40 and 41 providing offsets extending inwardly toward the center of the device to function as stops for establishing the normal position of the handle lever 42. The flange 39 has the circular hole 43 for rotatably receiving the shaft 44, and the flange 38 has a D-shaped hole 45 which non-rotatably receives the shaft in one angular position. The shaft 44 has a flat along one side indicated at 46, and a notch 47 intersecting one edge of the flat 46, as shown best in FIGURE 1. The functioning of this portion of the structure will be clarified as the description of the mechanism proceeds.

A cam unit 48 is rotatably mounted on the shaft 44, and includes the opposite end-sections 49 and 50 interconnected by the bar 51. The normal functioning of the cam member 48 is best illustrated in FIGURE 3. In locked position, the end portions 49 and 50, together with the cross bar 51, extend across the tongue 22 to maintain the interengagement of the apertures 25 and 26 with the abutments 28 and 29.

The normal position of the cam unit 48 is determined as a result of the interaction of the cam spring 52 and the engagement of the stops 53-54 on the lever 42 with the surfaces 55-56 on the cam unit 48. In other words, the action of the relatively light spring 52 is to apply a gentle rotary biasing action to the cam member 48 with respect to the lever. This rotative resilience of the cam member with respect to the lever in one direction permits the insertion movement shown in FIGURE 5. The insertion is accompanied by a movement of the tongue 22 of the buckle section 20 over the top of the abutments, and this must be accompanied by a counterclockwise rotation of the cam member (as shown in FIGURE 5) which is sufficient to permit the tongue 22 to pass underneath the bar 51 and the end portions 49 and 50. As the tongue 22 moves into the buckle section 30 to the point where the apertures 25 and 26 can drop down over the abutments 28 and 29, the upper surface of the tongue 22 comes down into close approximation to coplanar relationship with the top of the abutments. In this position, the action of the spring 52 can rotate the cam member 48 from the displaced condition shown in FIGURE 5 to that of the fully locked position shown in FIGURE 3. This action can take place without displacement of the lever 42. It should be noted that the fixed end of the spring 52 is a portion of constricted diameter shown at 57 which conforms to the D-shaped cross section of the shaft 44, and closely embraces it in a non-rotative relationship. The remainder of the spring 52 is rotatable with respect to the shaft 44. The end 58 of the spring engages the cross bar 51 of the cam member as best shown in FIGURE 2.

The spring 59 also surrounds the shaft 44, and functions to bias the lever to the position shown in FIGURE 3, applying a counterclockwise torque, as shown in the drawings. The spring 59 is similar in construction to the spring 52, except that it will normally be made of heavier wire to apply a stronger biasing action. The fixed end of the spring consists of a portion of reduced diameter shown

at 60 which conforms to the cross section of the shaft 44, and holds it securely in nonrotative relationship. The opposite end of this spring 61 engages the edge of the abutment 62 which is integral with the lever 42, and extends from the panel portion 63 to a position close to the shaft 44, with insufficient clearance for the free end 61 to slip out of engagement. The abutment 64 is also preferable in this arrangement, and fully embraces the shaft 44 with freedom of rotation. The abutment 64 is primarily for the purpose of maintaining the relative position of the abutment 62 and the shaft 44, and this structure is readily adaptable either to a die-cast or molded construction of the entire lever handle 42. In the event that molded plastic is used for the lever 42, the metallic bearing inserts shown at 65 and 66 are recommended for insertion into the ends 67 and 68, which establish the pivotal mounting of the lever with respect to the shaft 44 (in conjunction with the abutment 64). The surfaces 69 and 70 at the opposite ends of the lever 42, respectively, operate in conjunction with the lanced offsets 40 and 41 to establish the normal angular position of the lever shown in FIGURE 3, against the action of the spring 59. Recesses as shown at 71 in FIGURE 1 are associated with each of these shoulder surfaces 69 and 70 to provide clearance for rotation of the lever so that the stops 40 and 41 will not interfere with rotation of the lever to the release position.

As the lever is swung to the release position shown in FIGURE 4, the cam member 48 can follow this rotation under the action of the spring 52, or the cam member may be held initially in the FIGURE 3 position, if substantial forces are acting against it from the tongue 22. In the latter case, the rotation of the handle proceeds until the edge 72 comes into engagement with the ends 49 and 50 at the points indicated at 73 and 74 in FIGURE 1. The handle forces will then easily overcome the resistance against the rotation of the cam member, and the device can be moved to the FIGURE 4 position to permit release of the buckle section 20 from the buckle section 30. It should be noted that the full release position of the lever 42 shown in FIGURE 4 represents a swinging movement beyond the perpendicular to a line connecting the belt terminals on the opposite buckle sections. This movement exceeds ninety degrees, in the preferred form of the invention, and carries the lever beyond the position where inertia forces would conceivably bring it.

The assembly of the device is interesting in one particular, and this deals with the establishment of the necessary initial torsion in the springs 52 and 59. The procedure initially involves placing the lever so that the inserts 65 and 66 are in axial alignment with the holes 43 and 45, and the shaft 44 may then be inserted through the hole 43 and the insert 65. At this point, the shaft 44 is engaged with the spring 52, with the end 58 properly hooked over the cross bar 51 of the cam unit. The angular position of the shaft 44 is selected for proper engagement with the fixed end 57, and the shaft is then forced through this portion of the spring and through the bearing hole in the abutment 64. The shaft can then be given sufficient turns in a clockwise direction to establish the desired initial torsion in the spring 52, with an additional amount of turns in a clockwise direction corresponding to the amount of initial set of the spring 59. The shaft 44 may then be axially engaged with the end 61 of the spring 59, with the end 61 properly positioned with respect to the abutment 62. Prior to the engagement of the shaft 44 with the flange 38, the shaft is rotated in a counterclockwise direction an amount corresponding to the initial torque of the spring 59. The flat 46 of the shaft is then aligned with the D-hole 45, and the shaft 44 moved axially into engagement with the flange 38 to the point that the notch 47 will embrace the thickness of the flange. The shaft is then released, and is thereby fixed against axial displacement in either direction.

Referring to FIGURES 6 through 9, the modification of the invention illustrated in these views is preferable wherever it is desirable to minimize the weight of the buckle mechanism on the lap of the wearer. The adjustable terminal assembly generally indicated at 75 is dissociated from the tongue 76 which is releasably locked to the buckle section 77. The tongue plate 76 is connected to the adjustable terminal unit by a fixed length of belting shown at 78. It is preferable that a spacing of approximately eight inches be established between the terminal assembly 75 and the tongue plate 76, which normally places the terminal assembly far enough off the lap of the wearer so that it is no longer objectionable. The fixed cylindrical bar 79 and the movable bar 80 correspond to the bars 33 and 34, respectively, shown in FIGURE 1. The side flanges 81 and 82 serve the same function as the flanges 23 and 24 of the FIGURE 1 assembly, respectively. The tension portion 83 of the belt and the free end 84 are arranged in the same relationship as previously described.

The buckle section 77 is normally connected to the belt section 85, and contains a cam-type locking mechanism of the type shown and described in FIGURE 1 and the related views, with the exception that the handle lever 86 has a counterbalance feature in which a balance weight 87 is added to bring the center of gravity as close as possible to a plane containing the axis of the shaft 88, and which is perpendicular to the central plate portion 89 of the buckle section 77. In this arrangement, inertia forces encountered during a crash will have no substantial tendency to rotate the handle lever 86 in a clockwise direction to cause accidental release. In FIGURE 9, the lanced portions 90 and 91 serve the same purpose as the portions 40 and 41 in FIGURE 1. The flanges 92 and 93 are equivalent to the flanges 38 and 39, respectively, in FIGURE 1.

FIGURES 10 and 11 illustrate a modified form of the invention in which an aligned movement of the lever is provided by using a non-coaxial relationship between the cam member and the lever pivot. The buckle section 94 has spaced side flanges 95 which position the "D"-shaped lever shaft 96, together with the lever-return spring 97. The cam member 98 is rotatably mounted on the shaft 99, which is also positioned by the flanges 95, with the shaft 99 carrying the cam spring 100. In the position shown in FIGURE 10, the cam prevents the disengagement of the tongue plate 101 of the opposite buckle section from the abutments 102 on the plate portion 103 of the buckle section 94. The handle 104 has spaced side flanges as shown at 105 received between the flanges 95, and a rod 106 is fixed with respect to the flanges 105. Rotation of the handle 104 in a clockwise direction about the shaft 96 will carry the rod 106 upwardly, and the engagement of this rod with the extensions 107 on the cam member 98 will induce counter-clockwise rotation to the release position shown in FIGURE 11. The edges 108 of the flanges 105 can be used as stops to establishing the full release position of the lever, with these edges disposed to engage the plate 103 in the release position. Slots 109 may be provided in the flanges 95 to accommodate bars for an adjustable belt terminal, as described in connection with the views discussed previously.

The particular embodiments of the present invention which have been illustrated and discussed herein are for illustrative purposes only and are not to be considered as a limitation upon the scope of the appended claims. In these claims, it is my intent to claim the entire invention disclosed herein, except as I am limited by the prior art.

I claim:

1. A buckle assembly, comprising:

first and second buckle sections each having belt-receiving means, portions of said buckle sections being receivable one within the other, respectively;

interengageable abutments on said portions, respectively, said abutment means being engageable and separable in a direction transverse to a line connecting said belt-receiving means; a shaft normally fixed to the outer of said buckle sections adjacent said abutments, said shaft having an axially-extending peripheral discontinuity; a cam member rotatably mounted on said shaft, said cam member having portions disposed in a selected angular position thereof to maintain the interengagement of said abutments, and being rotatable in opposite direction from said selected position to positions providing for release and engagement of said abutments; a lever rotatably mounted on said shaft, and having stop means interengageable with portions of said cam member to limit the rotation of said cam member with respect to said lever to establish a limited sector of freedom of movement, said lever being rotatable from a normal position extending from said shaft toward the belt-receiving means associated with the inner of said buckle sections, said lever being rotatable to a release position through a sector in excess of ninety degrees bringing said cam member to release position; a lever-biasing helical spring surrounding said shaft and having one end thereof securely engaging the discontinuity of said shaft, the opposite end of said spring engaging the said lever urging the said lever to the said normal position thereof; and a cam-biasing helical spring surrounding said shaft and having one end thereof securely engaging the discontinuity of said shaft, the opposite end of said spring engaging the said cam member urging said cam member in the direction of rotation of said lever toward said release position, one of said stop means positioning said cam member against the action of said cam spring at said selected angular position when said lever is at said normal position; the said sector of freedom of movement of said cam member with respect to said lever being selected to provide for sufficient rotation of said cam member to provide clearance for the engagement of said abutments without substantial rotation of said lever from the said normal position thereof.

2. A buckle assembly, comprising:

first and second buckle sections each having belt-receiving means, portions of said buckle sections being receivable one within the other, respectively; interengageable abutments on said portions, respectively, said abutment means being engageable and separable in a direction transverse to a line connecting said belt-receiving means; a shaft normally fixed to the outer of said buckle sections adjacent said abutments;

said shaft having an axially-extending peripheral discontinuity;

a cam member rotatably mounted on said shaft, said cam member having positions disposed in a selected angular position thereof to maintain the interengagement of said abutments, and being rotatable in opposite direction from said selected position to positions providing for release and engagement of said abutments;

a lever rotatably mounted on said shaft, and having stop means interengageable with portions of said cam member to limit the rotation of said cam member with respect to said lever to establish a limited sector of freedom of movement, said lever being rotatable from a normal position extending from said shaft toward the belt-receiving means associated with the inner of said buckle sections, said lever being

rotatable to a release position bringing said cam member to release position;

a lever -biasing helical spring surrounding said shaft and having one-end thereof securely engaging the discontinuity of said shaft, the opposite end of said spring engaging the said lever urging the said lever to the said normal position thereof; and

a cam-biasing helical spring surrounding said shaft and having one end thereof securely engaging the discontinuity of said shaft, the opposite end of said spring engaging the said cam member urging said cam member in the direction of rotation of said lever toward said release position, one of said stop means positioning said cam member against the action of said cam spring at said selected angular position when said lever is at said normal position,

the said sector of freedom of movement of said cam member with respect to said lever being selected to provide for sufficient rotation of said cam member to provide clearance for the engagement of said abutments without substantial rotation of said lever from the said normal position thereof.

3. A buckle assembly, comprising:

first and second buckle sections each having belt-receiving means, portions of said buckle sections being receivable one within the other, respectively;

interengageable abutments on said portions, respectively, said abutment means being engageable and separable in a direction transverse to a line connecting said belt-receiving means;

a shaft normally fixed to the outer of said buckle sections adjacent said abutments,

said shaft having an axially-extending peripheral discontinuity;

a cam member rotatably mounted on said shaft, said cam member having portions disposed in a selected angular position thereof to maintain the interengagement of said abutments, and being rotatable to positions providing for release and engagement of said abutments;

a lever rotatably mounted on said shaft, and having stop means interengageable with portions of said cam member to limit the rotation of said cam member with respect to said lever to establish a limited sector of freedom of movement, said lever being rotatable from a normal position extending from said shaft toward the belt-receiving means associated with the inner of said buckle sections, said lever being rotatable to a release position bringing said cam member to release position;

a lever-biasing helical spring surrounding said shaft and having one end thereof securely engaging the discontinuity of said shaft, the opposite end of said spring engaging the said lever urging the said lever to the said normal position thereof; and

a cam-biasing helical spring surrounding said shaft and having one end thereof securely engaging the discontinuity of said shaft, the opposite end of said spring engaging the said cam member urging said cam member in the direction of rotation of said lever toward said release position, one of said stop means positioning said cam member against the action of said cam spring at said selected angular position when said lever is at said normal position.

4. A buckle assembly, comprising:

first and second buckle sections each having belt-receiving means, portions of said buckle sections being receivable one within the other, respectively;

interengageable abutments on said portions, respectively, said abutment means being engageable and separable in a direction transverse to a line connecting said belt-receiving means;

a shaft normally fixed to the outer of said buckle sections adjacent said abutments;

a cam member rotatably mounted on said shaft, said cam member having portions disposed in a selected angular position thereof to maintain the interengagement of said abutments, and being rotatable to positions providing for release and engagement of said abutments;

a lever rotatably mounted on said shaft, and having stop means interengageable with portions of said cam member to limit the rotation of said cam member with respect to said lever to establish a limited sector of freedom of movement, said lever being rotatable from a normal position extending from said shaft toward the belt-receiving means associated with the inner of said buckle sections, said lever being rotatable to a release position bringing said cam member to release position;

a lever-biasing spring urging the said lever to the said normal position thereof; and

a cam-biasing spring urging said cam member in the direction of rotation of said lever toward said release position, one of said stop means positioning said cam member against the action of said cam spring at said selected angular position when said lever is at said normal position.

5. A buckle mechanism, comprising:

a frame having spaced flanges;

a shaft rotatably engaging one of said flanges, and non-rotatably engaging the other of said flanges;

a lever and a locking member mounted on said shaft rotatably with respect to each other and to said frame;

a lever spring surrounding said shaft and having one end thereof rotatively fixed with respect to said shaft; and the opposite end thereof engaging said lever; and

a locking member spring surrounding said shaft and having one end thereof rotatively fixed with respect to said shaft and the opposite end thereof engaging said locking member, said springs applying opposite biasing to said lever and locking member, respectively.

6. In a structure as described, the combination of:

a frame having spaced flanges;

a shaft engaging said flanges;

means engageable with said shaft to fix the same rotatably with respect to said frame;

a lever and a locking member mounted on said shaft rotatably with respect to each other and to said frame;

a lever spring surrounding said shaft and having one end thereof rotatively fixed with respect to said shaft, and the opposite end thereof engaging said lever; and

a locking member spring surrounding said shaft and having one end thereof rotatively fixed with respect to said shaft and the opposite end thereof engaging said locking member, said springs applying opposite biasing to said lever and locking member, respectively.

7. In a structure as described, the combination of:

a frame;

a shaft mounted on said frame;

means engageable with said shaft to fix the same rotatably with respect to said frame;

first and second members mounted on said shaft rotatably with respect to each other and to said frame;

a spring surrounding said shaft and having one end thereof rotatively fixed with respect to said shaft, and the opposite end thereof engaging said first member; and

a spring surrounding said shaft and having one end thereof rotatively fixed with respect to said shaft and the opposite end thereof engaging said second mem-

ber, said springs applying opposite biasing to said members, respectively.
